UNITED STATES PATENT OFFICE.

HERMAN C. MAISE, OF DETROIT, MICHIGAN, ASSIGNOR TO BRIGGS MANUFACTURING COMPANY, OF DETROIT, MICHIGAN, A CORPORATION OF MICHIGAN.

VEHICLE BODY AND METHOD OF CONSTRUCTING THE SAME.

Application filed December 7, 1923. Serial No. 679,177.

This invention relates to vehicle bodies and method of constructing the same.

It is largely the practice today to construct vehicle bodies by first building up a skeleton framework of wood, metal, or the like, and applying to such framework, body plates or panels of metal; and it is one of the objects of the present invention to provide an improved construction of this general type, with a view to simplicity in design and construction and the method employed in the construction, improved appearance, in the resultant structure, increased wear-resisting properties to the vehicle body finish, coupled with strength and durability.

In carrying out the invention it is proposed to form a suitable skeleton framework, and to apply to such framework pre-shaped or prefashioned metal panels or plates, and to provide novel and improved means of covering and protecting the adjacent edges of the panels, to the end that the said panel edges are concealed and the connecting means for said covering means will, itself, be concealed; and in this connection it is to be borne in mind that while the means for protecting and covering the panel edges are designed primarily for automobile bodies, the invention in this particular is susceptible of a variety of adaptations, all of which are within the spirit of the invention.

It is also contemplated by the present invention to subject the prefashioned panels, prior to assembly on the framework, to suitable enameling and baking processes, and further to form said panels at their securing edges in a manner so as not to crack, mar, or otherwise injure the finished surface of the body portion of the panels when securing the same in place by a fastening means engaging said edges.

More particularly, the invention includes the construction of a framework, the formation of panels which have been subjected to prefashioning, enameling, and baking processes, the application and securing of said panels to the framework, applying at the meeting edges of the panels overlying protecting strips or moldings, and the securing of said strips in place by means connected with, though concealed by the exposed portions of the strips, themselves.

A still further feature of the invention

resides in the provision of securing means, such as bolts, rivets, or the like, for the joined covering strips or moldings, which, though mounted upon the strips, are adjustable with respect thereto, to the end that fixed points of connection or cooperating securing means, such as bolt-receiving recesses, may be provided at suitable spaced points on the frame, and when the strips are applied, said securing means may be readily moved into a proper position with respect to the strip whereby to register with the appropriate cooperating bolt-receiving recess of the frame. Other improvements and novel details in the construction and arrangement of the parts, and the novel steps in the method employed, will be appreciated from the description to follow, which for a clear understanding of the invention is to be considered in connection with the accompanying drawing forming a part hereof, and wherein is disclosed for the purpose of illustration, a convenient and satisfactory embodiment of the invention; though it is to be borne in mind, in this connection, that various changes may be resorted to without departing from the spirit of the invention.

In the drawings:

Figure 1 is a perspective view of a portion of a vehicle frame having preshaped and pre-enamelled panels in accordance with my invention, the panels being secured in place to the frame of the vehicle in any desired manner, and parts of the panels being broken away;

Figure 2 is a similar view, disclosing in addition means for concealing adjoining edges of the panel sections;

Figure 3 is an enlarged view partly in perspective and partly in section, showing panel sections applied to a frame with concealing means for the meeting edges of the panel sections;

Figure 4 is a transverse section of adjacent panels and supporting frame therefor, with concealing means for the adjacent edges of the panels, and securing means (in elevation) for the concealing means;

Figure 5 is an enlarged detail of a portion of one of the preshaped panels, broken away;

Figure 6 is a view similar to Figure 3, with the concealing means removed; and

Figure 7 is a detail view with parts cut away and partly in section, illustrating a

slightly modified construction of concealing means.

With more particular reference to the drawings, wherein like reference numerals refer to corresponding parts throughout the several views, a suitable skeleton framework 1 is provided, conveniently of wood, and taking any approved form.

The said framework includes parts 2 to which are adapted to be secured the body plates or panels. These plates or panels 3 are preferably formed of metal, and it is one of the objects of the invention to pre-shape or prefashion these panels, and to subject the same to enameling and baking processes prior to the application of the same to the framework, in order that when secured in position a series of cooperating prefashioned panels will assume the desired curvature of the completed vehicle body.

It has been ascertained that difficulty has some times been experienced in assembling prefashioned panels having enamel applied thereto, because of injury to the enameled surface incident to the application of the securing means. In other words, the portions of the enameled surface adjacent the securing edges thereof sometimes become dented, and the enameling cracked or otherwise marred during the securing operation; and in order to effectively overcome this possibility, it is proposed to provide the panels at their securing edges with inwardly offset portions 4 having at suitable intervals tongues or extensions 5 to which latter are applied the securing means such as bolts or rivets 6 adapted to engage the frame member 2. The projecting tongue 5 of the securing edges of the panels form therebetween elongated cutout parts or recesses 7 of a length considerably greater than the width of the tongues 5, whereby the recesses 7 of the securing edges of one panel member will constitute receiving chambers for the tongues of a cooperating panel members, the tongues and recesses on the adjacent panel members being arranged in alternate relation; and because of the length of the recesses 7, there will be no difficulty in registering the tongue of one panel with the receiving chambers of the cooperating panels, regardless of slight irregularities in the assembly of the panels. The projecting tongues 5 of the panels being of considerable width with respect to the cutaway portions of the securing edges 4 of the panels allows of the application of the securing bolts, rivets, or nails 6 at a point considerably removed from the body portion of the panels, to the end that in the application of such securing means the body portion of the panels will not be damaged; and because of the enlarged area provided for the securing means, a more secure fastening is made possible.

It is also desirable to provide the spaces 7 between the projecting tongues 5 of a length considerably greater than that necessary for the tongue, whereby to leave an exposed area of the frame 2 between the overlapping tongues of respective panels when assembled. In these exposed portions of the frame 2 are positioned suitable bolt or rivet holes 8 for a purpose about to be described.

It is desirable, of course, to provide means for concealing the adjacent edges of the panels together with the securing means therefor, and one of the features of the invention includes a novel form of molding or covering strip adapted to overlie said adjoining edges of the panels and to be effectively secured to the frame. In the preferred embodiment of this feature of the invention, the covering member conveniently takes the form of a channel bar comprising a body part 9 and inwardly turned flanges 10. The member 9-10 may take different designs and configurations but is preferably curved so as to present a substantially C-shaped cross section, whereby the curvature of the body portion 9 will give a pleasing outward appearance as well as allow for the curvature of headed bolts or the like 11, the shanks of which are adapted to project into or through the openings 8 in the frame 2 and to be secured in place as by nuts 12, engaging threaded terminals 13 of said bolts. The bolts, as suggested, have headed nuts 14 adapted to be seated in the channel formed between the inwardly turned flanges 10 and the body portion 9 of a covering strip or molding, the engaging between the headed end of the bolts 14 and the channel being a loose one, whereby the bolts are readily adjustable by a sliding movement lengthwise with respect to the covering strips 9-10, to the end that the bolts may be readily brought into registration with the cooperating receiving recesses 8 positioned at any desired predetermined position in the frame 2 at points in the spaces between the tongues 5 of the adjoining channels 3. Securing means for the covering members other than that specifically illustrated may be provided, assuming that such securing means is of such a character as to be adjustable with respect to the covering strip, whereby to register as desired, with the cooperating securing means arranged at fixed points on the frame.

In the modified form of construction illustrated in Figure 7, it is suggested that the covering or finishing strip 9-10 may be secured in place by means of suitable tacks, bolts, or the like 17, but in this embodiment of the invention it is desirable to utilize a supplemental covering strip (see 15 of Figure 3) to conceal such retaining means.

The covering strips 9-10 may, if desired, and preferably are, subjected to enameling

and baking processes prior to their application, in order that the appearance may correspond largely with that of the finish of the body panels 3. On the other hand, since it has been found that at times the covering plate may become dented or otherwise marred, by the securing of the bolts 11 in place by the securing nuts, it is contemplated by the invention to provide an overlying supplemental strip or molding comprising a body part 15 and yieldable inwardly turned side flanges 16 of relatively shallow depth, but shaped to correspond with the general curvature of the main covering strips 9—10, to the end that the supplemental covering strip may under slight pressure be snapped over the main covering strips 9—10 and thus be yieldably held in place. Where the supplemental covering strips 15—16 are employed it may not be necessary to subject the main covering strip 9—10 to enameling and baking processes, but it is preferable to subject the supplemental covering strip to such enameling and baking operations before application.

The present invention makes possible the preliminary prefashioning of the panel plates and the finishing of the same by enameling and baking prior to the application of the framework, since such finishing of the plates will not be disturbed or marred by the securing of the panels in position; and by reason of the peculiar securing means provided, the panels will be effectively mounted, and a strong and durable body results.

By reason of the novel type of molding and securing means for the latter, it is not necessary that the openings 8 in the framework be accurately positioned, since they readily adapt themselves one to the other by the adjustable characteristics incident to the mounting of the bolts on the covering. Again, the bolts being carried by the covering, in the channel part thereof, the covering constitutes a concealing medium for its own securing means.

Because of the staggered arrangement of the tongues which project from adjacent panels, it will be appreciated that the edges of adjacent panels may be brought into closer registration than in prior constructions; and this also makes possible the use of a covering or concealing strip of molding of less width than in prior constructions, which not only enhances the appearance of the vehicle body as a whole, but also tends to reduction in the cost of manufacture.

What I claim is:

1. The method of constructing vehicle bodies, comprising the formation of a framework of wood or the like, pre-fashioning metal panels to form the exterior body, forming offset edge flanges on said panels, subsequently subjecting said pre-fashioned metal

panels before application to the framework to an enameling process, securing the panels at said offset flanges only to the framework whereby to prevent marring of the enameled surfaces, and applying concealing strips to the joints between adjacent edges of the panels by means concealed by the concealing strips.

2. A vehicle body construction comprising a framework, metallic plates having offset edges secured to the framework, molding overlying the joints between the plates, and means connecting with and covered by the molding to secure the latter in place independently of the plates.

3. In a vehicle body, the combination of a skeleton frame, plates or panels secured to said frame and having edges with cut out parts, means for concealing the adjoining edges of the plates, the frame having spaced openings arranged adjacent said cut out parts, and securing means for said concealing means adjustably positioned on the interior of the latter whereby to register with said openings.

4. In a vehicle body having adjoining plates with portions of said adjoining plates overlapping, means for securing said overlapping portions to the frame of the vehicle body, a concealing strip for the securing means and the overlapping portions of the joints between the plates, and securing means for said concealing strip, mounted upon and itself concealed by said strip.

5. A panel for vehicle bodies, comprising a pre-fashioned and pre-enameded metallic body part, and securing edges offset inwardly with respect to the pre-fashioned body part, whereby securing means may be applied to the offset edges without harmful effect on the pre-fashioned and pre-enameded body part of the panels.

6. A prefashioned panel for vehicle bodies, having an offset securing edge with cut-out parts forming alternate tongues and recesses.

7. In a vehicle body, the combination of cooperating body panels, with adjacent securing edges having projecting tongues, the tongues on the edges of one panel being arranged in alternate relation with the tongues of adjacent panels.

8. A vehicle body construction comprising a framework, cooperating body panels or plates with adjacent securing edges having projecting tongues, the tongues of the edges of one panel being arranged in alternate relation with the tongues of adjacent panels, a covering strip adapted to overlie adjacent edges of the panels, and securing means projecting from the strip and engaging the framework in the recess between the tongues of adjacent panels.

9. In an automobile body, a plurality of adjoining panel plates, said plates at

their adjoining edges having overlapping tongue and groove parts, means for securing the tongues in place, a molding strip overlying said tongues and grooves, and 5 means independent of the tongue-securing means for securing said molding strip in place.

10. In an automobile body, the combination of panel plates having at their adjoining edges inwardly offset flanges whereby the plates may be secured at said flanges to the body portion of the vehicle without likelihood of damaging the body portion of the panels, and a molding strip of a width 15 to overlie said offset edges and the body portion of the plates connecting with said edges.

11. In an automobile body, the combination of a frame, metal panel plates having spaced securing tongues offset inwardly from the body portion of said plates, the spaces between the tongues of one plate being adapted to receive the tongues of an adjacent plate, and the tongues of adjacent 25 plates being separated laterally by spaces, a covering strip adapted to overlie the securing tongues, and securing means for the covering strip adapted to engage the wooden frame at points in registration with the 30 spaces between said tongues.

12. In a vehicle body construction, the combination with a frame member, of metal panels spaced apart on said frame member, the adjacent edges of said panels having laterally spaced staggeredly arranged attaching tongues, securing means for said panels engaging the said tongues, molding concealing said tongues and the adjacent edges of said panels, and securing means for 35 said molding extending between the laterally spaced tongues and engaging said frame member.

13. In a vehicle body, the combination with a frame member, of metal panels posi-

tioned on said frame member, the metal 45 panels having pre-fashioned body portions and edges, with laterally spaced staggeredly arranged attaching tongues, the spaces between the tongues being of substantially greater width than the width of the tongues, 50 securing means for said panels engaging the tongues and out of contact with the body portion of the panels, molding concealing 55 said tongues and the adjacent edges of said panels, and securing means for said molding extending into the space between the laterally spaced tongues and engaging said frame member.

14. In a vehicle body construction, the combination of a frame part, adjacent panel 60 members having pre-fashioned and pre-enamelled surfaces prior to application to the frame part, and said panels also having at their adjacent edges offset flanges extending substantially parallel with the body of the 65 panels, means for securing said offset edges directly to the frame part, whereby in the application of the panels the preshaped and pre-enamled surfaces will not be damaged, the said adjacent flanges having cut out 70 parts forming alternate tongues and grooves, with the tongues of the flange on one panel lying within the space of the grooves of the adjacent panel and said grooves being of a 75 width somewhat greater than the length of the tongues whereby to provide an intermediate space, and a molding adapted to overlie the adjacent edges of the panels, and means carried by the molding and lengthwise movable with respect thereto adapted 80 to be secured directly to the frame part by passing through the space between the tongues and grooves of the edges of the panels.

In testimony whereof I hereunto affix my 85 signature.

HERMAN C. MAISE.
